UNITED STATES PATENT OFFICE.

HENRY DOULTON, OF LAMBETH, COUNTY OF SURREY, AND JOHN SLATER,
OF BURSLEM, COUNTY OF STAFFORD, ENGLAND.

ORNAMENTING CHINA AND EARTHEN WARE AND OTHER POTTERY.

SPECIFICATION forming part of Letters Patent No. 314,002, dated March 17, 1885.

Application filed February 10, 1885. (No model.) Patented in England March 27, 1882, No. 1,476.

To all whom it may concern:

Be it known that we, HENRY DOULTON, of Lambeth, in the county of Surrey, England, and JOHN SLATER, of Burslem, in the county 5 of Stafford, England, subjects of the Queen of Great Britain, have invented certain new and useful Improvements in Ornamenting China and Earthen Ware and other Pottery, (for which we have received Letters Patent in Great 10 Britain, No. 1,476, dated March 27, 1882;) and we do hereby declare that the following 15 is a full, clear, and exact description of the invention, which will enable others skilled in the art to which it appertains to make and use the same.

This invention has for its object improvements in ornamenting all kinds of pottery, including china and earthen ware. For this purpose we employ textile fabrics--such as lace-- 20 with which we impress or indent the surface of the clay.

One method is to lay the lace or other suitable material upon the surface of the clay, pressing it in a sufficient depth, and covering 25 the surface, either wholly or in part, with color or colored clays, which may be either dry or damp, according to the effect wished for. The lace or other material is then removed, and the clay placed in the mold and pressed in the 30 ordinary way.

Another method is to apply the lace or other suitable material to the surface of a roller, and to bring the roller so clothed against the clay or article in process of manufacture, and when 35 of a suitable consistency to take the impression; or a shallow recess may be made in the surface of the article and the lace or other suitable material laid therein. Then, by pressure with a suitable tool--such as a burnishing-

tool--the lace is embedded in the surface of 40 the clay. It may then, if deemed requisite, be stripped off, leaving the impression.

What we claim is—

1. The process of ornamenting china and earthen ware and other pottery by impressing 45 textile fabric—such as lace—upon the clay, together with the application of color or colored clay, and pressing the clay so embossed in plaster or other molds, substantially as described.

2. The process of ornamenting china and earthen ware and other pottery by indenting the surface of the clay by means of rollers covered with lace or such like material, substantially as described.

3. The process of ornamenting china and earthen ware and other pottery by forming a shallow recess in the surface of the article, covering the recessed part with textile fabric—such as lace—and by a burnisher or like tool 60 causing the fabric to be impressed into the clay, substantially as described.

In testimony whereof we have hereunto set our hands in the presence of two subscribing witnesses.

HENRY DOULTON.
JOHN SLATER.
